UNITED STATES PATENT OFFICE.

EGBERT H. GOLD, OF CHICAGO, ILLINOIS.

ATTACHMENT FOR HEATING SYSTEMS.

No. 895,177.

Specification of Letters Patent.

Patented Aug. 4, 1908.

Original application filed December 14, 1905, Serial No. 291,759. Divided and this application filed October 26, 1906. Serial No. 340,662.

To all whom it may concern:

Be it known that I, EGBERT H. GOLD, a citizen of the United States, residing at Chicago, in the county of Cook and State of Illinois, have invented certain new and useful Improvements in Attachments for Heating Systems, of which the following is a specification.

This invention relates to improvements in fluid heating apparatus and is particularly adapted for use in conjunction with the steam supply of a car-heating system, or other fluid distributing system, wherein it is desirable that no condensed fluid be permitted to remain in the radiating or other pipes after the supply of steam has been shut off.

The object of my invention is to provide means by the use of which the condensed fluid is permitted to drip from a waste or outlet pipe but is not permitted to become frozen as it drips from said pipe and thereby close the latter. This and such other objects as may hereinafter appear are accomplished in the device illustrated in the accompanying drawings, in which—

Figure 1 is an elevational view of apparatus illustrating my invention; and Fig. 2 shows a cross-section taken on the line 2—2 of Fig. 1 looking downward.

In the several figures of the drawing, A is the floor of a car, B is an inlet or feed pipe which takes steam or other heating fluid from the train pipe. This pipe B communicates through an elbow C and short pipe D with the valve casing E.

The valve casing may contain a valve of the form shown in my co-pending application Serial No. 291,759, or said valve may be of any desired form by means of which means are provided for establishing communication between the feed pipe and the radiating system when the valve is open while, when the valve is closed and the supply of fluid shut off, communication is established between the radiating system and the atmosphere; so that fluid condensing in the radiating system may find its way out of the same. Any form of valve may be employed which effects this result, but the valve herein shown and more fully described in the co-pending application referred to has been found to be well suited to this purpose.

In practice it has been found that one of the difficulties to be overcome is that of preventing the freezing in the drip pipe of the

fluid which condenses in the radiating system and finds its way out through said drip pipe. Such freezing, of course, clogs the drip pipe, or even closes the same wholly. F is the pipe leading from the valve casing to the radiating system and G the drip pipe leading downward from the valve E. The means by which I overcome the objection referred to is that of providing a heat conducting member adapted to embrace the steam supply pipe and the drip pipe, so that the drip pipe will be kept warm by conduction of heat from the hot steam pipe thereto.

In the form of my invention which is illustrated in the drawings I provide a pair of yoke members H and I, these members being hinged together at J. The yoke members are of such a form that each pipe is practically completely inclosed in the metal of the yokes. Each of the yoke members is perforated at its end opposite the end which is hinged to the other yoke member. Through these perforated ends is passed a bolt K which is provided with a nut L, by the tightening of which the yoke members are drawn into firm contact with the feed pipe and drip pipe.

In installing heating apparatus in cars it is important that such a connection as is herein shown shall be adjustable, for the reason that the various pipes and attachments found beneath the car and between its floors vary so in different cars. For example, the pipes B and F may approach their connections at different angles from those shown in Fig. 1 of the drawings. This will necessitate arrangements of pipes G and D in a variety of different positions relative to each other; and involves the construction of the connection between the feed pipe and the drip pipe so that it may be accommodated for different relative positions of these pipes.

In practical construction I preferably provide the elbow C, and by making it very heavy and fitting the yoke members around this elbow I obtain the most efficient heat retaining and heat conducting device, and I prefer in such construction that the elbow shall be formed with a wide neck M at one of its ends adapted to be closely embraced by the yoke members H and I. Obviously, however, it is of secondary importance as to what part of the feed pipe is engaged by the yoke members and the relative weight of the yoke members and parts to which they are

attached is a matter of choice to suit varying conditions.

I prefer to thread the upper ends of the pipes G and D or otherwise provide for a connection between these pipes and the valve casing E which will permit their rotation.

In Fig. 2 I have shown in full lines the supply pipe B approaching from one direction and in dotted lines the same approaching from another direction, and I have also illustrated in dotted lines one of various alternative positions of the drip pipe G with reference to the vertical portion D of the feed pipe.

15 It will be seen that generically my invention contemplates the use of means formed of metal, or other good heat conducting material, adapted to embrace the supply pipe of a fluid heating system and the waste pipe

20 which carries off the condensation from said system, whereby the waste pipe is heated and the products of condensation prevented from becoming frozen and obstructing said waste pipe.

25 This is a division of my co-pending application Serial No. 291,759, filed December 14, 1905.

I claim:

1. The combination with a casing, of a 30 pipe leading from the valve casing and adapted to be connected with a radiating system, a drip pipe leading from said casing, a feed pipe, a pipe connection extending from the casing to the feed pipe and comprising an 35 elbow to connect the same with the feed pipe, a part of said connection being rotatable relative to the casing, and removable yoke mem-

bers engaging the lower end of said connection and the drip pipe all arranged so as to accommodate for different angular positions 40 of the feed pipe and the pipe leading to the radiating system.

2. The combination with a valve casing, of a pipe leading from said casing and adapted to be connected with a radiating system, 45 a drip pipe leading from the valve casing, a feed pipe, a pipe connection leading from the feed pipe to the valve casing, said connection being connected with the valve casing by a joint permitting its rotation with respect 50 thereto, and removable yoke members engaging with the lower end of said connection and with said drip pipe, all arranged so as to accommodate for different angular positions 55 of the feed pipe and the pipe leading to the radiating system.

3. The combination with a valve casing, of a pipe leading from the valve casing and adapted to be connected to the radiating system, a drip pipe leading from said valve casing, a feed pipe, an elbow connected with the feed pipe, a connecting pipe leading from the elbow to the valve casing, said connecting pipe connected with the valve casing by a joint permitting its rotation, and removable 60 yoke members connecting the elbow with the drip pipe, all arranged so as to accommodate for different angular positions of the feed pipe and the pipe leading to the radiating system.

EGBERT H. GOLD.
